US00D757782S

(12) **United States Design Patent**
Moriya

(10) **Patent No.:** **US D757,782 S**
(45) **Date of Patent:** **** May 31, 2016**

(54) **DISPLAY SCREEN WITH GRAPHICAL USER INTERFACE**

(71) Applicant: **AXELL CORPORATION**, Tokyo (JP)

(72) Inventor: **Kazuyoshi Moriya**, Tokyo (JP)

(73) Assignee: **AXELL CORPORATION**, Tokyo (JP)

(**) Term: **15 Years**

(21) Appl. No.: **29/543,009**

(22) Filed: **Oct. 20, 2015**

Related U.S. Application Data

(63) Continuation of application No. 29/451,196, filed on Mar. 28, 2013, now Pat. No. Des. 743,980.

(30) **Foreign Application Priority Data**

Nov. 30, 2012 (JP) 2012-029364

(51) **LOC (10) Cl.** **14-04**

(52) **U.S. Cl.**

USPC **D14/486**

(58) **Field of Classification Search**

USPC D14/485-495

CPC G06F 3/048; G06F 3/0482

See application file for complete search history.

(57) **CLAIM**

The ornamental design for a display screen with graphical user interface, as shown and described.

DESCRIPTION

The FIGURE is a front view of a display screen with graphical user interface showing my new design.

The broken lines showing of the display screen with graphical user interface are for environmental purposes only and form no part of the claimed design.

1 Claim, 1 Drawing Sheet
